(57) **CLAIM**

The ornamental design for a multifunction cleaning brush, as shown and described.

DESCRIPTION

FIG. 1 is a front, perspective view of a multifunction cleaning brush showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front perspective view thereof, showing the multifunction cleaning brush in an open state of use;

FIG. 9 is another front perspective view thereof, showing the multifunction cleaning brush in an open state of use; and,

FIG. 10 is a front perspective view thereof, showing the multifunction cleaning brush in a state of use.

The broken lines in the drawings depict portions of the multifunction cleaning brush that form no part of the claimed design.

1 Claim, 10 Drawing Sheets
